UNITED STATES PATENT OFFICE.

JOHN REUTHER, OF EAST AURORA, NEW YORK.

POTATO-DIGGER.

No. 922,816.

Specification of Letters Patent.

Patented May 25, 1909.

Application filed March 13, 1908. Serial No. 420,794.

To all whom it may concern:

Be it known that I, JOHN REUTHER, a citizen of the United States, residing at East Aurora, in the county of Erie and State of New York, have invented a new and useful Improvement in Potato-Diggers, of which the following is a specification.

This invention relates more particularly to elevator potato-diggers, comprising a plow, shovel or digging blade, an endless elevator or separator which receives the potatoes, earth and vines from the plow and effects a preliminary separation of the potatoes from the soil and vines, and a shaker or secondary separator which receives the potatoes and remaining soil and vines from the tail of the elevator and effects a final separation thereof.

One of the objects of the invention is the construction of a simple, compact and efficient machine of this class which is comparatively inexpensive.

A further object is to improve the construction of the elevator with a view of increasing its separating capacity, rendering it more durable and avoiding clogging thereof.

In the accompanying drawings consisting of three sheets: Figure 1 is an enlarged longitudinal section of the machine, the draft pole and truck being omitted. Fig. 2 is a vertical longitudinal section of a portion of the elevator, on an enlarged scale. Fig. 3 is a sectional top plan view of the machine. Fig. 4 is a fragmentary longitudinal section of the elevator at right angles to Fig. 2. Fig. 5 is a vertical longitudinal section in line 5—5, Fig. 3, showing one of the roller-scrappers of the elevator. Fig. 6 is a fragmentary longitudinal section in line 6—6, Fig. 5. Fig. 7 is a transverse section of the machine in line 7—7, Fig. 1. Fig. 8 is a longitudinal section in line 8—8, Fig. 3, on a reduced scale. Fig. 9 is a front elevation of one of the cranked rods of the elevator. Fig. 10 is a top plan view of the front portion of the machine.

Similar characters of reference indicate corresponding parts throughout the several views.

A indicates the main axle of the machine to which the ground wheels A¹ are secured in the customary manner. Upon this axle the main frame is supported which comprises forwardly-inclined side bars B, vertical extensions B¹ depending from the rear ends of the side bars, a rear tie-rod b connecting the lower ends of said extensions and a front tie-

rod b¹ connecting the front portions of the side-bars B and preferably made of cranked construction with its main body portion offset rearwardly, as shown at b², for the purpose hereinafter described. As shown in Fig. 8, the axle A is mounted in bearings or hangers C secured to the side-bars B.

The plow or shovel may be of any suitable construction. For digging in ordinary soils, the usual single-pointed plow or shovel may be employed. When, however, the machine is used in soil covered with crab grass, the digging device preferably consists of a pair of pointed blades or shovels D, D arranged side by side and secured to a pair of carrying arms D¹ secured to the front ends of the side-bars B and bent inwardly under the blades, as shown, each of these arms carrying one of the blades. The pitch or angle of convergence of the sides of these blades is comparatively sharp, as shown, so that crab grass will not catch on the blades and pile up thereon, which is liable to occur when a single blade with abrupt edges is used, but the same will be deflected and pass freely over the surface of the blades onto the elevator, preventing clogging or obstruction of the machine.

As shown in Figs. 3 and 10, the rear portions of the blades are separated, say about an inch, to form a narrow throat or passage through which a part of the crab grass passes. This spaced arrangement of the twin-blades also has the important advantage that it does not divide the soil but allows it to remain intact and pass in that condition onto the elevator. If the blades were arranged close together, the soil would be divided and some of it with the adhering potatoes would be liable to escape laterally from the blades before reaching the elevator.

As shown in the drawings, the elevator or endless separator which is arranged immediately behind the blades D consists of a pair of endless chains, belts or carriers E and cranked transverse rods or bars F carried by the chains. In the preferred construction shown, these carriers consist of sprocket chains running with their front portions around smooth guide rollers g journaled on the end portions of the tie-rod b¹, and with their rear portions around sprocket wheels g¹ secured to a transverse shaft g² supported in hangers or bearings g³ carried by the rear portions of the side-bars B, as best seen in Fig. 8. On the ends of the shaft g² are

mounted gear pinions g^4 meshing with gear wheels g^6 secured to the axle A whereby the elevator is driven from the latter. The lower sides of the chains are supported by sprocket 5 wheels g^6 carried by the main frame of the machine.

g^7 indicates scrapers carried by the main frame and running in contact with the front guide rollers g for detaching any adhering 10 soil and insuring a free action of the elevator-chains.

The rods F extend across the full width of the elevator and are provided at their end portions with crank arms f terminating in 15 journals or wrist-pins f^1 which turn freely in openings or bearings in the chains E. In the construction shown in the drawings, these wrist-pins are journaled centrally in the chain-links, and the crank arms of the rods 20 are of such a length that the end portions of each rod overlap the crank arms of the next adjacent rod, as best shown in Figs. 1, 2 and 4, so that said cranked end portions form stops whereby the rods on the upper side of 25 the elevator are supported in their normal elevated position. The rods, while thus limited in their downward movement when on the upper side of the elevator, are free to swing upwardly and rearwardly without restraint, so as to drop into a pendent position 30 upon passing around the rear sprocket wheels g^1 and while on the underside of the elevator, as shown in Fig. 1. The rods are arranged so closely together that the potatoes are 35 prevented from falling through the spaces between them; and the rods are preferably round, as shown, but may be of any other suitable cross section, if desired. By offsetting the front tie rod b^1 rearwardly, as shown, 40 a sufficiently wide space is left between the same and the elevator-rods F to prevent stones from lodging at this point and blocking the elevator.

An agitator of any suitable construction is 45 preferably arranged to coöperate with the elevator-rods F on the upper side of the elevator for shaking them and loosening and breaking up the soil. The preferred agitator shown in the drawings consists of a series of 50 smooth-faced rollers H journaled on horizontal studs h carried by a longitudinal supporting bar or frame I¹. This frame is arranged centrally underneath the upper side of the endless elevator and extends nearly from end 55 to end thereof. This frame is vertically adjustable, so that the rollers H may be raised to a greater or less extent into the path of the elevator-rods F, thereby compelling the rods to trip over the rollers and agitating them 60 more or less vigorously. The rollers are properly spaced to allow an elevated rod to drop upon the adjacent rod after clearing the roller and before mounting the next roller. For this purpose, the rollers are preferably 65 spaced to engage alternate rods and ar-

ranged in staggered order on opposite sides of the supporting bar I¹, as shown in Figs. 1 and 3.

In the construction shown in the drawings, the bar I¹ is carried at its rear end by a link j pivoted upon the axle A, and near its front end by an arm j¹ secured to a transverse rock shaft J carried by the side-bars B and having a hand-lever J¹ for turning it. This shaft is locked in position by any suitable means, the device shown in the drawings, Fig. 3, consisting of a catch j² interlocking with a notched segment j³ carried by the frame of the machine.

L, L¹ indicate the shaker which receives 80 the potatoes, vines and any remaining soil from the delivery end of the elevator and effects a final separation of the potatoes from the vines and soil in a manner common to this class of machines. The shaker may be 85 of any suitable construction.

U is a seat-supporting yoke or frame which straddles the elevator and is secured at its sides to the side-bars B of the main frame and the side or guard plates U¹ of the elevator.

V indicates a draft-truck of any suitable construction, V¹ the draft pole and W draft bars connecting the main frame of the machine with the truck.

x indicates a hand-lever for vertically adjusting the front portion of the frame which carries the blades D and the elevator, said lever being connected with the seat-yoke by links x¹.

The operation of the machine is as follows: The potatoes, soil and vines dug up by the blades D pass upon the receiving end of the elevator which conveys the mass rearwardly, the greater portion of the soil falling between 105 the rods F of the elevator and the potatoes and vines dropping over the tail of the elevator upon the head of the shaker which separates any remaining earth from the potatoes.

The rods F on the upper side of the elevator 110 are normally raised, so as to lie in the plane thereof, and as the rods trip over the elevated agitating rollers H they are vigorously shaken, thus loosening the earth and breaking up the lumps sufficiently to pass between 115 the rods. The lifting of the rods as they pass over these rollers widens the space between them and facilitates the escape of the detached soil and any stones, and this action together with the smooth or toothless construction of the rods materially increases the 120 separating capacity of the machine. As the rods pass around the rear sides of the sprocket wheels g^1 , they swing by gravity to the reversed or pendent position shown in 125 Fig. 1, and upon ascending around the front guide wheels g they again assume their normal elevated position in which they are supported by resting upon one another's cranked ends.

The elevator-rods, which may be made of steel or wrought iron, are very strong and yet present comparatively narrow supporting surfaces which tend to cut the soil and from 5 which the latter readily falls. The rods are therefore subjected to correspondingly less weight or strain and are not liable to bend, sag or break, as is the case when they are constructed to present a wide surface. As 10 the rods by this construction carry a smaller quantity of soil, they afford the further advantage that they can be more easily agitated, thus enabling the machine to be drawn by the animals with less exertion. 15 Another important advantage of providing the elevator rods with cranked ends is that they are capable of swinging farther apart upon reaching the lower side of the elevator. In case comparatively large stones should fall 20 upon such lower rods, they are free to separate sufficiently to release and discharge them, thus preventing such stones from being carried between the elevator chains and the front guide wheels *g* and breaking or obstructing the elevator. 25

I claim as my invention:—

1. In a potato digger, the combination of a separator comprising carriers and transverse separating rods provided with crank-arms by 30 which they are journaled in the carriers, said rods being spaced to intercept potatoes, means for limiting the swinging movement of the rods during a portion of their travel, and means for delivering the material upon the 35 separator, substantially as set forth.

2. In a potato digger, the combination of a separator comprising endless carriers and transverse separating rods provided at their 40 ends with crank arms having wrist pins journaled in said carriers, said rods being spaced to intercept potatoes, means for holding the rods in their normal elevated position on the upper side of the separator, while permitting them to swing to a pendent position on the 45 lower side of the separator, the rods when at the lower side of the separator being free to

swing away from each other to increase the space between them, and means for delivering the material upon the separator, substantially as set forth. 50

3. In a potato digger, the combination of a separator comprising endless carriers and transverse separating rods provided at their ends with crank arms having wrist pins journaled in said carriers, said rods being spaced 55 to intercept potatoes and the cranked end- portions of adjacent rods being arranged to overlap one another to support the rods in their normal elevated position while on the upper side of the separator, and means for 60 delivering the material upon the separator, substantially as set forth.

4. In a potato digger, the combination of a separator comprising endless carriers and transverse separating rods provided with 65 crank arms having wrist pins journaled in the carriers, said rods being spaced to intercept potatoes, means for supporting the rods in their normal elevated position while on the upper side of the separator, means for agitating the rods on the upper side of the separator, and means for delivering the material upon the separator, substantially as set forth. 70

5. In a potato digger, the combination of a 75 separator comprising endless carriers and transverse separating rods provided with crank arms journaled in the carriers, said rods being spaced to intercept potatoes, a support arranged underneath the upper side 80 of the separator, agitating rollers mounted on said support in staggered order and adapted to project into the path of said rods, and means for delivering the material upon the separator, substantially as set forth. 85

Witness my hand this 11th day of March, 1908.

JOHN REUTHER.
